UNITED STATES PATENT OFFICE.

CHRISTOPHER C. BRADLEY, OF SYRACUSE, NEW YORK.

THILL-COUPING.

SPECIFICATION forming part of Letters Patent No. 634,549, dated October 10, 1899.

Application filed April 24, 1899. Serial No. 714,235. (No model.)

To all whom it may concern:

Be it known that I, CHRISTOPHER C. BRADLEY, a citizen of the United States, residing at Syracuse, in the county of Onondaga and

5 State of New York, have invented new and useful Improvements in Thill-Couplings, of which the following is a specification.

This invention relates to that class of thill-couplings which comprise a divided draft-eye 10 on the vehicle and a wrist or knuckle on the thill or pole iron, which wrist or knuckle is adapted to be seated in the draft-eye and is held therein by a fastening device applied to the latter and so constructed that the draft-eye 15 can be quickly opened or closed for shifting from a pole to thills, or vice versa. When a divided packing or washer of leather or similar material is used on the wrist or knuckle, it is liable to drop off in removing the latter 20 from the draft-eye. Heretofore the packing has been retained on the wrist or knuckle by a fine wire, which is passed through openings near the longitudinal meeting edges of the 25 divided packing and which has its ends twisted together.

The object of this invention is to provide the packing with a simpler and more satisfactory fastening device.

In the accompanying drawings, Figure 1 is 30 a vertical longitudinal section of a thill-coupling provided with my improvement. Fig. 2 is a vertical cross-section in line 2 2, Fig. 1. Fig. 3 is a perspective view of the wrist of the thill-iron with the packing applied thereto. Fig. 4 is a detached side view of the spring-clasp by which the packing is held on its 35 wrist. Fig. 5 is a perspective view of a modified construction of the packing.

Like letters of reference refer to like parts 40 in the several figures.

A represents the front axle of a vehicle, and B the clip, whereby the thill-coupling is secured to the axle. The coupling represented in the drawings is of well-known construction 45 and comprises a lower fixed jaw C, which is secured to the under side of the axle and projects forwardly therefrom, a movable upper jaw D, which is hinged to the front end of the fixed jaw, a clamping-lever E, which is 50 arranged underneath the fixed jaw and piv-

oted to the end of a bent tension-spring F, and a bail or loop G, which connects the lever with the movable jaw. The fixed and movable jaws constitute the draft-eye.

H represents the thill or pole iron, and h 55 the wrist or knuckle of the same. The latter may be of any suitable form, but is preferably approximately spherical and arranged between the side bars h' of the thill-iron, as shown. 60

I represents the packing, which surrounds the wrist h, and is seated in corresponding cavities in the jaws of the draft-eye. The packing corresponds in form with that of the wrist and is, as shown, approximately spherical in form. It is made of a flat piece of hard-oak leather bent and molded by pressure between dies to the required form, with the open joint i extending along one side, so that this divided or split packing will retain 65 its shape, but can be sprung over the wrist. The packing is provided in its outer surface midway between its ends with a circumferential groove k, in which is placed a spring-bow or divided spring-clasp L. The latter is 70 sprung into this groove after the packing has been applied to the wrist and holds the packing securely on the latter. When the wrist, with its packing, is seated in the closed draft-eye, the spring-clasp is embedded in the 75 groove and does not in any way interfere with the working of the parts, particularly since the packing does not turn in the draft-eye, but the wrist turns in the packing as the thill or pole iron rocks up and down. Upon removing the wrist from the draft-eye the spring-clasp holds the packing securely on the wrist, but is readily sprung off if the packing is to be renewed. 80

The packing is preferably saturated with 85 tallow or some other suitable lubricant.

I prefer to form the packing of a single piece; but, if desired, it may be made in halves, as shown in Fig. 5, in which case it has two longitudinal open joints i'. 95

I claim as my invention—

1. The combination with the draft-eye and the draft-wrist, of a divided packing which surrounds the draft-wrist and which is adapted to be seated in the cavity of the draft-eye, 100

and a narrow, divided spring-clasp which embraces the packing and retains the same on the draft-wrist when the latter is removed from the draft-eye, substantially as set forth.
5 2. The combination with the draft-eye and the draft-wrist, of a divided packing which surrounds the draft-eye and which is provided in its outer surface with a narrow, circumferential groove, and a divided spring-clasp which is seated in said groove and re-

tains the packing upon the draft-wrist when the latter is removed from the draft-eye, substantially as set forth.

Witness my hand this 18th day of April, 1899.

CHRISTOPHER C. BRADLEY.
